UNITED STATES PATENT OFFICE.

CHARLES S. CHAMBERLAIN, OF EMERYVILLE, CALIFORNIA.

DISH-WASHING MACHINE.

SPECIFICATION forming part of Letters Patent No. 760,777, dated May 24, 1904.

Application filed July 23, 1903. Serial No. 166,767. (No model.)

To all whom it may concern:

Be it known that I, CHARLES S. CHAMBERLAIN, a citizen of the United States, residing at San Pablo avenue and Forty-fifth street, 5 Emeryville, in the county of Alameda and State of California, have invented certain new and useful Improvements in Dish-Washing Machines; and I do hereby declare the following to be a full, clear, and exact description of said 10 invention, such as will enable others skilled in the art to which it most nearly appertains to make, use, and practice the same.

This invention relates to improvements in dish-washing machines, and has for its object 15 the thorough washing of dishes in large bulk without breaking or chipping and with the minimum effort and maximum speed.

Broadly, the invention consists of a table 20 having two wells having parallel walls and adapted to respectively contain washing and rinsing water, both being provided with means for maintaining the water boiling or at any desired temperature. The dishes are stacked 25 within a bucket having a perforated bottom, (wire-netting,) being securely held in position by a rack. The walls of the bucket are parallel with the walls of the wells with a slight 30 clearance, which permits the bucket to be rapidly raised and lowered, whereby a piston action is secured, the movement being produced by the windlass mounted in a traveling crane adapted to travel the length of the 35 table to successively present the bucket to the washing and rinsing wells.

In the drawings, Figure 1 is an end elevation of a washing-machine constructed in accordance with this invention, the table, well, and bucket being shown in cross-section on the line X X, Fig. 2. Fig. 2 is a front elevation 40 of the same on a reduced scale. Fig. 3 is a plan view of the bottom of the bucket. Fig. 4 is a perspective of the rack for holding the dishes within the bucket.

In detail the construction consists of the table A, supported on the legs A' and provided with the splash-rail A² to lead the splash-water back into the wells. The wells B and B' are hermetically attached to the under side of the table coincident with suitable openings there-

through, the weight being supported by the 50 legs B³, resting upon the floor C.

The bucket D consists of a cylinder adapted to telescope loosely with the walls and having a bottom D', of wire-netting, secured therein a slight distance above the lower edge of the 55 walls of the bucket. For convenience of handling the bucket is provided with a bail D². The rack D³ is laid in the bucket on top of the wire-netting. Into this rack the flat dishes are set on edge, the smaller dishes being suitably disposed in the remaining space. The 60 washing is accomplished by rapidly raising and lowering the bucket within the well, which contains scalding-water with strong soap or suitable alkali solvents therein. In constructing the bucket it is vitally important that the bottom D' be placed slightly above the lower edge of the bucket-wall. This forces the water up through the body of the bucket and its 65 contents. If the bottom of the bucket were 70 flush, the displacement would be lateral, forcing the water up the sides between the bucket and well sides.

This present construction is calculated for 75 restaurant and hotel use, where a large bulk of dishes have to be handled, to facilitate which the windlass E, operated by the crank E', upon which the belt E² from the bucket and over the pulley E³ is wound. To further expedite handling, the frame F, in which the 80 windlass mechanism is mounted, is adapted to travel the length of the table on the rollers F', engaging the tracks F², secured to the table. One of said tracks F² is mounted on an elevated support F³, whereby the bucket 85 D may be readily reached without interference from the frame F.

The wells are adapted to be filled with hot water from the service-pipe G through the 90 valves G'. Each well is provided with the upper and lower drains H and H'. The supply and drain pipes, provided with suitable valves, admit of a regulation to preserve a determined level of flowing water in each well. The drains H and H' lead to a main 95 drain Z, extending along floor C, and a gas or oil heater I is provided under each well to keep up the temperature of the water.

Knives, forks, spoons, and the like are more satisfactorily washed separately from the other dishes. The construction of the bucket and well are similar in every respect to that 5 described above except as the size of the machine, the table and traveling crane being omitted and a lid added to the bucket. The forks are dropped into the bucket tines down, so that they protrude through the bottom of 10 the bucket, the other articles being thrown in indiscriminately. When the bucket is raised and lowered (by hand) within the well, the water is shot upward among the articles, and the protruding tines of the forks striking 15 the bottom of the well scrape against the wire-netting of the bottom of the bucket, effectually dislodging any food lodged between the tines.

In operation the bucket is set on the table 20 at the left end and loaded with dishes, then hooked to the belt E², raised by the windlass, carried forward coincident with the first well, and lowered thereinto and the dishes effectively washed as described, then raised and 25 rolled forward and lowered into the second well and then roughly rinsed in the water therein,

raised and rolled forward and set down on the right end of the table in reach of the dish-wiper, this process being carried on constantly without the necessity of the operative 30 lifting any weight in excess of the heaviest single dish.

Having thus described this invention, what is claimed, and desired to be secured by Letters Patent, is—

A dish-washing machine comprising a table supporting wells adapted to contain water, a track located on one side of said table, a second track located on the opposite side of the table and elevated above the plane of the 40 former track, a frame having an overhanging portion bearing on said elevated track, a windlass carried by said frame, and a bucket detachably connected to said windlass and adapted to be reciprocated in said wells. 45

In testimony whereof I have hereunto set my hand this 30th day of June, 1903.

CHARLES S. CHAMBERLAIN.
